SHEET FOLDING AND DELIVERING MECHANISM

Application filed March 28, 1930. Serial No. 439,637.

The invention relates to new and useful improvements in sheet folding and delivering mechanisms, and more especially to such improvements in said mechanisms adapted to fold and deliver running webs from fast rotary perfecting printing presses and the like.

Objects and advantages of the invention will be set forth in part hereinafter and in part will be obvious herefrom, or may be learned by practice with the invention, the same being realized and attained by means of the instrumentalities and combinations pointed out in the appended claims.

15 The invention consists in the novel parts, construction, arrangements, combinations and improvements herein shown and described.

The accompanying drawings, referred to herein and constituting a part hereof, illustrate one embodiment of the invention, and together with the description serve to explain the principles of the invention.

Of the drawings:—

26 Fig. 1 is a vertical transverse section through two cooperating cutting and folding cylinders and delivering mechanisms, embodying the invention;

Fig. 2 is an end elevation of the same mechanism looking therat from the front of the sheet;

Fig. 3 is a fragmentary top plan of the other ends of the cylinders;

Fig. 4 is a detached detail of the actuating cam for the impaling pin mechanism on the collecting cylinder;

Fig. 5 is a section view taken on line 5--5 of Fig. 4;

Fig. 6 is a detached detail view of the other interchangeable part of the impaling pin cam mechanism, for straight or collecting runs;

Fig. 7 is a detached detail of the actuating mechanism for the impaling pin mechanism on the smaller cylinder;

Fig. 8 is a diagram of a cam for operating the pins on the large folding cylinder on straight runs, and

Fig. 9 is a diagram of a cam for operating the pins of said cylinder when collecting,

The invention is directed to mechanism especially capacitated to cut and fold off the sheets, or groups thereof, collected or uncollected, from very fast running webs, for instance, the perfected and longitudinally-folded webs of fast rotary newspaper presses. 55

In accordance with one feature of the invention, such mechanisms are capacitated to alternatively deliver the folded-off products to a plurality of delivery mechanisms, each of such mechanisms receiving the product from a particular folding-off mechanism, and thereby reducing by one-half the speed of the folding-off and delivery with respect to the press speed. 65

These and other functions and advantages are realized and embodied by the present invention in a very simple and compact mechanism, the operating devices or parts thereof being preferably of reliable and tested design and operation, thereby insuring reliability of operation, absence of stoppages and breakages, and other faults, while maintaining the desired high speed of product output. 70

Referring in detail to the embodiment of the invention illustrated by way of example in the accompanying drawings, a cylinder 1 is shown provided with sheet cutting, sheet-holding and releasing, and sheet-folding mechanisms, and a cooperating cylinder 2 is provided with like devices. These cooperating cylinders and their attendant mechanisms are capacitated to take the running webs from the printing press or other source of supply, to cut same into sheets and either to fold the cut-off sheets alternately from one cylinder and its folding mechanism and then from the other cylinder and its folding mechanism, or to collect on one of said cylinders and to fold off therefrom the entire product from said source of supply into a single folding mechanism. In the application of the present invention to fast rotary perfecting printing presses, the perfected webs, usually four pages wide, are centrally slit, the two halves being run over a pair of formers, and then directed to the two cylinders to be operated on in one of the alternative ways as already described. It will be understood 10

that other sources of web supply may be provided as may be desired.

In said exemplary embodiment, a cylinder 1 is provided with a shaft 5, and suitable supporting heads 6, the shaft 5 being journaled in the side frames 7 at either side of the press. Said cylinder as embodied is a three-way cylinder, that is, it has three sheet-carrying surfaces arranged about its periphery. The cylinder 10 is provided with suitable sheet-cutting devices cooperating with corresponding devices upon the cylinder 2. As embodied, the cylinder 1 has three female cutting members 12, 13 and 14. In this present embodiment 15 the diameter of the cylinders 1 and 2 is in the ratio of three to two, and accordingly the cylinder 2 is provided with two cooperating male cutting members 15 and 16.

The sheet taking and releasing means may 20 be of various forms so far as concerns the broader aspects of the invention, but for fast newspaper work, and as shown, impaling pins of the usual type are provided. The cylinder 1 is provided with three sets, 21, 22 and 23, of 25 impaling pins, each set cooperating with one of the sheet-cutting devices to take the lead of the web immediately after the sheets are cut in the usual manner. In each of the impaling pin devices, the series of pins are mounted 30 in a bar 26 carried upon arms 27, fixed upon a shaft 28, the shaft 28 being journaled in the heads of the cylinder 1. The shaft 28 projects from the cylinder head at one end, and on the projecting end of the shaft is fixed an 35 arm 29, upon which is mounted a cam roller 30 which runs on the cam for timing the operation of the pins to take and to release the sheets in proper time, either for the alternate folding off arrangement of the mechanism 40 or for the collecting and folding off of the entire product by the cylinder 1. On the actuating mechanism for impaling pins 22 the same reference numerals are applied with an *a*, and for pins 23 a *b* is added. This 45 variable setting of the timing and operation of the impaling pins is controlled by a rotating cam mechanism, which will be later described.

The cylinder 2 of the present embodiment 50 is provided with only one set of sheet-taking, holding and releasing devices, shown as a set of impaling pins 33 mounted upon a bar 34, which bar is carried upon arms 35, fixed to a shaft 36, journaled in the heads 55 of the cylinder. One end of the shaft projects from the cylinder 36, and attached thereto is an actuating arm 37 which carries a cam roller 38, which cooperates with a controlling cam mechanism later to be described. Said mechanism is constructed and arranged so that the set of impaling pins 33 may be operated each time they come to sheet-cutting position, or may be totally silenced. For this purpose a disc 40 is fixed on the end 60 of shaft 36 and arm 37 extends beyond the

shaft. Between this extension and disc 40 is a bolt and slot connection 41, by adjustment of which the throw of the impaling pins can be changed whereby they do not project outside the cylinder and this acts, to prevent the impaling action without disconnecting the mechanism. The other cutting device 15 upon the cylinder 2, has no cooperating set of impaling pins, as consecutive sheets are not taken from the running webs upon cylinder 75 2 as the machine is here exemplarily organized.

The embodied form of folding off mechanisms upon cylinder 1 comprises a plurality of single-edge rotatable folding blade mechanisms, one set being located at each of the sheet-holding surfaces on the cylinder. The folding device 45 has a single folding blade 46, mounted on a shaft 47, which shaft is journaled in the cylinder heads. The shaft 47 has one end projecting from the cylinder 1, and fixed to said shaft end is a cross-bar 48, carrying cam rollers 49 and 50 at either end thereof. These cam rollers run on a circular track 51 of the kind commonly used 80 with the so-called "Husby" cam movement.

The folding mechanism 55 has a single folding blade 56, mounted on a shaft 57, which is journaled in the cylinder heads. On the end of shaft 57 which projects from the cylinder head is mounted a cross-bar 58, at the ends of which are mounted a pair of cam rollers 59 and 60, which likewise run on track 51, and are actuated by the rotating cam at the folding position. In 95 like manner, folding mechanism 65 has a single folding blade 66, fixed on a shaft 67, journaled in the cylinder heads. To the projecting end of the shaft 67 is fixed a cross-arm 68, on which is mounted a pair of cam rollers 69 and 70, which likewise run on the cam track 51 and coat with the rotary cam at the folding-off position.

The rotary actuating cam, as embodied, 100 comprises a cam disc 77 fixed to and rotating with a stub shaft 78, mounted on the machine frame. The cam 77 is provided with two cam slots 79 and 80, which cooperate with the cam rollers on the folding devices, these cam slots being arranged in substantially 105 tangential relation to a circle concentric with the cam shaft. The cam is rotated by a gear 81 fixed thereto, which meshes with a gear 82, fixed on the shaft 5 of the cylinder 1. The cam has a three-to-two ratio of revolution to the cylinder, and therefore actuates each of the folding mechanisms each time 110 that it passes the cam.

Cooperating with the folding blades are 115 a pair of folding-off rollers 85 and 86, which are shown more or less conventionally, and which may be of any known or other suitable type. A delivering mechanism takes the papers from the folding-off rollers 85 and 86, and same is indicated generally in Fig. 120 130

1 of the drawings by reference numeral 87. It may comprise a star wheel and a delivery belt of the usual or common form.

The folding mechanism 91 on the cylinder 2 is double-bladed, having two blades 92 and 93 fixed to a shaft 94, which is journaled in the cylinder heads. On the end thereof which projects from the head of the cylinder 2 shaft 94 is provided with a cross-bar 95 at the ends of which are mounted cam rollers 96 and 97. These cam rollers run on a fixed circular cam track 98. Cooperating therewith is the rotary cam 99, mounted on the shaft 100, journaled on the machine frame. Fixed to the cam disc is a gear wheel 101 which cooperates with a gear wheel 102, fixed on the shaft 103 of cylinder 2, which latter shaft is journaled in the machine frame. The cam 99 is provided with three cam slots 104, 105 and 106, which are tangentially positioned in the manner already described. Cooperating with the folding mechanism in the cylinder 2 are two folding-off rollers 109 and 110, which are adapted to deliver the folded papers to a rotary delivery mechanism indicated generally at 111, which may comprise a star wheel and traveling delivery belt of known form. The cam 99 makes four revolutions for three revolutions of the cylinder 2, and actuates the folding mechanism every time it passes the folding rollers.

As regards the operation of the folding mechanism when running "straight", that is, when one group of sheets cut from the running web is taken by and is folded off from cylinder 1, and the next group is taken by and folded off from cylinder 2, the mechanism may be regarded as in the position or Fig. 2, and the web leads as having been taken by the impaling pins 23. When the folding mechanism 65 reaches the folding-off rollers 85 and 86, it is actuated and the folding blade 66 folds off the sheets between the folding rollers. The next lead of the web is taken by the cylinder 2, in a manner hereafter to be described. The impaling pins 22 of cylinder 1, therefore, do not take the web, but pass the sheet-cutting position retracted within the cylinder.

When the folding mechanism 55 reaches the folding-off rollers 85 and 86, the folding mechanism is actuated, but due to there being but a single folding blade, the folding blade 56 at this time moves within the cylinder during the semi-rotation of the shaft 57, and there is no folding-off action, which is proper, as there are no sheets on the section. When the folding off mechanism 45 reaches the folding position, it is actuated and the folding blade 46 folds off the sheets in the usual manner. When folding mechanism 65 next reaches the folding position, it is actuated, but the folding blade 66 rotates within the cylinder, and there are no sheets on

this section of the cylinder, and therefore no folding off. When folding mechanism 55 next passes the folding position it is actuated and folding blade 56 folds off the sheets from the cylinder. When folding mechanism 45 again passes the folding position it is actuated, but the blade 46 rotates within the cylinder and there are no sheets on the section and therefore no folding off. This completes one cycle of operation of the folding mechanism.

The folding mechanism is the same whether the mechanism is run "straight" or "collect". When the mechanism is run "straight", every other group of sheets cut from the webs is delivered to cylinder 2 and every alternate sheet supporting space on cylinder 1 consequently passes the folding position vacant and this corresponds to the non-folding actuation of the particular folding mechanism. When the machine is run "collecting", and all the products are taken by and folded off from the cylinder 1, the non-folding actuation of each folding mechanism corresponds to the collecting period for the particular sheet supporting section. That is the first group of sheets is carried past the folding position, and the second group of sheets is taken upon the first group, and as so collected, they are folded off together on the next passage of the folding off rollers.

Referring now to the folding-off action of cylinder 2, it may be considered that the impaling pins 33 are in the projected position and are carrying a group of sheets, as the folding mechanism 91 comes to the folding-off rollers 109 and 110, the impaling pins 33 are retracted, and the sheets are folded off by either folding blade into the bight of the folding-off rollers 109 and 110. The next time the impaling pins pass the sheet-cutting position, they are retained in the retracted position, and do not take the lead of the web, which has been taken by one of the sets of impaling pins on the cylinder 1, and on this half rotation the folding mechanism of cylinder 2 is actuated idly.

Referring now to the embodied form of means for timing and actuating the impaling pin mechanisms on the cylinder 1 (Figs. 1, 3, 8 and 9), the cam rollers 30, 30^a and 30^b of the respective impaling pin mechanisms run in a rotatable groove cam 121. Cam 121 is integral with or fixed to a gear wheel 122, mounted loosely on shaft 5 of cylinder 1, and has interchangeable parts or members whereby it is operated on straight running or to collect. A gear wheel 123 is fixed on shaft 103 of cylinder 2 to turn therewith, and meshes with the loose gear wheel 122. Intermeshing gear wheels 124 and 125 are fixed, respectively, on the shafts 5 and 103, to cause the two cylinders to rotate together in the required three to two ratio. The gears 122

and 123 are proportioned to effect the required relative rotation between cam 121 and cylinder 1, and therefore the impaling pin actuating cam rollers. In the illustrated embodiment cam 121 makes three revolutions to two revolutions of cylinder 1, and in the same direction.

In the embodied form, the shape of the cam track is changed to adapt cylinder 1 for 10 straight running or for collecting, and for this purpose it is split as shown in Figs. 4, 5 and 6. The interchangeable member 121^a is employed for straight runs and the like interchangeable part 121^b is used for collecting 15 on cylinder 1.

Considering the cam in form for straight runs (Figs. 8) the cam makes three revolutions to two revolutions of cylinder 1 and in the same direction. Impaling pins A (which 20 may be any given set of pins) are in the projected position and take the web lead at α on the cam. The pins A then rotate 150° to the point Y, where they are retracted into the cylinder to release the sheets, which at that 25 instant are cut off and folded into the folding-off rollers 85 and 86. The low point L on the cam, which is 75° behind the pins A, when in the position of Fig. 8 (that is, when taking the web lead), rotates 225° while 30 the pins A are rotating 150° from α to γ (that is, from sheet-taking to sheet-releasing positions), and thereby the cam roller M for the pins A and the low L on the cam coincide at Y and the pins are retracted, thereby 35 releasing the sheets as they are folded off.

When the set of pins B are at position A, they must be retracted within the cylinder, as the lead of the web is then taken by the impaling pins on cylinder 2. The rotation of 40 pins B from the position of Fig. 8 to position A is 120°, and during this rotation of pins B from the position of Fig. 8 to position of Fig. 8, and this puts the low side of the cam at position A, and pins B are thereby 45 retracted within the cylinder and do not take the web lead.

When pins C have reached position A, they must project, as cylinder 1 again takes the web lead as was the case with pins A. 50 The rotation of the pins from their position in Fig. 8 to position A is 240°, and during this rotation the cam rotates 360° (and is thus again in the position shown in Fig. 8), and pins C are projected and take the lead of 55 the web. The entire cycle then repeats with the pins C, in the manner already described with relation to pins A, and later the same thing occurs with respect to the pins B. Thus, every alternate time the web lead is 60 taken by cylinder 1 and on the other time by cylinder 2, the folding-off occurring as has already been described.

Considering now the machine as set for collecting by cylinder 1, the interchangeable 65 split cam shown in Figs. 4 and 8 has been

replaced by the cam shown in Figs. 6 and 9. The cam, of course, still makes three revolutions to two revolutions of the cylinder 1, and in the same direction as the cylinder. In the position shown in Fig. 9, the pins A are projected and take the lead end of the web, the corresponding sheet-taking surface having come up to this position bare after the collected product has been folded off. At this time pins B have one sheet or group, 70 and will take another sheet or group thereon when position A is reached. The pins C are just about to release the collected product at the instant of folding-off.

Pins A are projected at position A of Fig. 80 9, and must stay out during one complete rotation of cylinder 1, to impale the web lead which is just being taken in Fig. 9 and to then again impale the web lead to collect the second sheet or group upon the first, 85 and must remain out until point Y is reached, where the pins must be retracted to release the collected product at the instant of folding-off. The complete rotation of the pins A from the point of taking the first 90 web lead, past the taking of the second web lead, and to the position Y with the collected product is 510°, and the cam rotates during this time 765°. Thus the low part L of the 95 cam and the actuating roller for the pins A coincide at the point Y, and thereby the pins A are retracted, and the collected product folded off.

Pins B must project beyond the cylinder until they reach point A to take the second web lead to complete the collection of the two products, and must continue projected until they reach the point Y. At that point they must be retracted within the cylinder to release the collected product at the instant of folding-off. The rotation of pins B from the position shown in Fig. 9, to the point Y is 270°, and during the same time the cam rotates from the position shown in Fig. 9, through 405°, which brings the low L of the cam to the point Y coincidentally with the actuating roller for the pins B, which are retracted and the collected product is folded off.

Pins C must rotate from the position shown in Fig. 9 through 30° to the point Y, and during that time the low point L on the cam rotates 45°, which brings them together at Y, and the pins C are retracted, and the collected product is folded off. The sequence then begins again with pins A.

It will be understood that the plates will be positioned on the opposite halves of the form cylinders of the various printing couples so as to get properly folded product at either delivery.

The invention in its broader aspects is not limited to the specific mechanisms shown and described but departures may be made therefrom within the scope of the accom-

panying claims without departing from the principles of the invention and without sacrificing its chief advantages.

What I claim is:—

5. 1. A sheet folding and delivery mechanism including in combination a plurality of cooperating folding cylinders, a plurality of delivery mechanisms, and means for delivering the entire folded product to one delivery mechanism or a part thereof to each of a plurality of delivery mechanisms and for collecting a part of the product. 70
10. 2. A sheet folding and delivery mechanism including in combination a plurality of cooperating folding cylinders, a plurality of delivery mechanisms, optionally usable collecting means, and means for delivering the entire folded product to one delivery mechanism or a part thereof to each of a plurality of delivery mechanisms. 80
15. 3. A sheet folding and delivery mechanism including in combination a plurality of cooperating folding cylinders, a plurality of delivery mechanisms, optionally usable collecting means, and means for delivering a folded product to one delivery mechanism and a succeeding folded product to another delivery mechanism. 85
20. 4. A sheet folding and delivery mechanism including in combination a plurality of cooperating folding cylinders, a plurality of delivery mechanisms, optionally usable collecting means, and means for delivering the product from one folding mechanism to one delivery mechanism and the folded product from another folding mechanism to a different delivery mechanism. 90
25. 5. A sheet folding and delivery mechanism including in combination a plurality of cooperating folding cylinders, a plurality of delivery mechanisms, optionally usable collecting means, and means for delivering the folded product from one folding mechanism to one delivery mechanism and the folded product from another folding mechanism to a different delivery mechanism. 95
30. 6. A sheet folding and delivery mechanism including in combination a plurality of cooperating folding cylinders, a plurality of delivery mechanisms, optionally usable collecting means, and means for delivering the folded products from a plurality of folding devices to a single delivery mechanism. 100
35. 7. A sheet folding and delivery mechanism including in combination a plurality of cooperating folding cylinders, means on said cylinders coacting to cut sheets from a web, a plurality of delivery mechanism, optionally usable collecting means, and means for delivering the entire folded product to one delivery mechanism or a part thereof to each of a plurality of delivery mechanisms. 105
40. 8. A sheet folding and delivery mechanism including in combination a plurality of cooperating folding cylinders, means on said cylinders coacting to cut sheets from a web, a plurality of delivery mechanisms, optionally usable collecting means, and means for delivering a folded product to one delivery mechanism and a succeeding folded product to another delivery mechanism. 110
45. 9. A sheet folding and delivery mechanism including in combination a plurality of cooperating folding cylinders, means on said cylinders coacting to cut sheets from a web, a plurality of delivery mechanisms, optionally usable collecting means, and means for delivering successive folded products alternately to different delivery mechanisms. 115
50. 10. A sheet folding and delivery mechanism including in combination a plurality of cooperating folding cylinders, means on said cylinders coacting to cut sheets from a web, a plurality of delivery mechanisms, optionally usable collecting means, and means for delivering the folded product from one folding mechanism to one delivery mechanism and the folded product from another folding mechanism to a different delivery mechanism, or for delivering the folded products from a plurality of folding devices to a single delivery mechanism. 120
55. 11. A sheet folding and delivery mechanism including in combination a plurality of cooperating folding cylinders, a plurality of delivery mechanisms, means for optionally collecting sheets upon one of said cylinders, and means for delivering the entire folded product to one delivery mechanism or a part thereof to each of a plurality of delivery mechanisms. 125
60. 12. A sheet folding and delivery mechanism including in combination a plurality of cooperating folding cylinders, a plurality of delivery mechanisms, means for optionally collecting sheets upon one of said cylinders, and means for delivering successive folded products alternately to different delivery mechanisms. 130
65. 13. A sheet folding and delivery mechanism including in combination a plurality of cooperating folding cylinders, a plurality of delivery mechanisms, means for optionally collecting sheets upon one of said cylinders, and means for delivering the folded product from one folding mechanism to one delivery mechanism and the folded product from another folding mechanism to a different delivery mechanism, or for delivering the folded products from a plurality of folding devices to a single delivery mechanism. 135
70. 14. A sheet folding and delivery mechanism including in combination a cylinder having sheet holding and releasing means and folding means, a cylinder coacting therewith and having sheet holding and releasing means and folding means, folding off rollers cooperating directly with both of said cylinders and means for immediately folding off the product directly from both said cylinders. 140

ders or for folding off all the product from one of said cylinders.

15. A sheet folding and delivery mechanism including in combination a cylinder having sheet holding and releasing means and folding means, a cylinder coacting therewith and having sheet holding and releasing means and folding means, folding off rollers cooperating directly with both of said cylinders, optionally usable sheet collecting means and means for immediately folding off the product directly from both said cylinders or for folding off all the product from one of said cylinders.

15 16. A sheet folding and delivery mechanism including in combination a cylinder having sheet holding and releasing means and folding means, a cylinder coacting therewith and having sheet holding and releasing means and folding means, folding off rollers cooperating directly with both of said cylinders, means whereby a product is folded off either cylinder to one of the folding off mechanisms or a part of the sheets are collected and all the product is folded off from one cylinder to a single folding off mechanism.

17. A sheet folding and delivery mechanism including in combination a cylinder having sheet holding and releasing means and folding means, a cylinder coacting therewith and having sheet holding and releasing means and folding means, folding off rollers cooperating directly with both of said cylinders, means whereby a product is folded off either cylinder to one of the folding off mechanisms or a part of the sheets are collected upon one of the cylinders, and all the product is folded off from said cylinder.

40 18. A sheet folding and delivery mechanism including in combination a cylinder having sheet cutting means, sheet holding and releasing means and folding means, a cylinder coacting therewith and having cooperating sheet cutting means and silenceable sheet holding and releasing means and folding means, and a plurality of delivery devices, the folded products of said cylinders being deliverable to one or to a plurality of said delivery devices.

45 19. A sheet folding and delivery mechanism including in combination a cylinder having thereon a plurality of sheet cutting means, sheet holding and releasing means and folding means a cylinder coacting therewith and having cooperating sheet cutting means, and silenceable sheet holding and releasing means and folding means, and a plurality of delivery devices, the folded products of said cylinders being deliverable to one or to a plurality of said delivery devices.

50 20. A sheet folding and delivery mechanism including in combination a cylinder having sheet holding and releasing means

and folding means, a cylinder coacting therewith and having silenceable sheet holding and releasing means, and folding means, and a plurality of delivery devices, the folded products of said cylinders being deliverable to one or to a plurality of said delivery devices.

70 21. A sheet folding and delivery mechanism including in combination a cylinder having thereon a plurality of sheet holding and releasing means and folding means, a cylinder coacting therewith and having silenceable sheet holding and releasing means and folding means, and a plurality of delivery devices, the folded products of said cylinders being deliverable to one or to a plurality of said delivery devices.

75 22. A sheet folding and delivery mechanism including in combination a cylinder having sheet cutting means, sheet holding and releasing means and folding means, a cylinder of different circumferential dimension coacting therewith and having cooperating sheet cutting means and silenceable sheet holding and releasing means and folding means, and a plurality of delivery devices, the folded products of said cylinders being deliverable to one or to a plurality of said delivery devices.

80 23. A sheet folding and delivery mechanism including in combination a cylinder having thereon a plurality of sheet cutting means, sheet holding and releasing means and folding means, a cylinder of different circumferential dimension coacting therewith and having cooperating sheet cutting means, and silenceable sheet holding and releasing means and folding means, and a plurality of delivery devices, the folded products of said cylinders being deliverable to one or to a plurality of said delivery devices.

85 24. A sheet folding and delivery mechanism including in combination a cylinder having sheet holding and releasing means and folding means, a cylinder of different circumferential dimension coacting therewith and having a silenceable sheet holding and releasing means and folding means, and a plurality of delivery devices, the folded products of said cylinders being deliverable to one or to a plurality of said delivery devices.

90 25. A sheet folding and delivery mechanism including in combination a cylinder having thereon a plurality of sheet holding and releasing means and folding means, a cylinder of different circumferential dimension coacting therewith and having silenceable sheet holding and releasing means and folding means, and a plurality of delivery devices, the folded products of said cylinders being deliverable to one or to a plurality of said delivery devices.

95 26. A sheet folding and delivery mechanism including in combination a three-way folding cylinder, having three folding de-

devices, a cooperating two-way folding cylinder having a single folding means and a single sheet holding and releasing means, a pair of folding off rollers cooperating with said three-way folding cylinder and a pair of folding off cylinders cooperating with said two-way folding cylinder, and devices on said folding cylinders for cutting sheets from a running web.

10 40. A sheet folding and delivery mechanism including in combination a plurality of cooperating folding cylinders, means thereon for taking the web leads from a printing press, a plurality of delivery mechanisms, and means for delivering the entire folded product to one delivery mechanism or a part thereof to each of a plurality of delivery mechanisms.

20 41. A sheet folding and delivery mechanism including in combination a plurality of cooperating folding cylinders, means thereon for taking the web leads from a printing press, a plurality of delivery mechanisms, and means for delivering a folded product to one delivery mechanism and a succeeding folded product to another delivery mechanism.

30 42. A sheet folding and delivery mechanism including in combination a plurality of cooperating folding cylinders, means thereon for taking the web leads from a printing press, a plurality of delivery mechanisms, and means for delivering successive folded products alternately to different delivery mechanisms.

40 43. A sheet folding and delivery mechanism including in combination a plurality of cooperating folding cylinders, means thereon for taking the web leads from a printing press, a plurality of delivery mechanisms, and means for delivering the folded product from one folding mechanism to one delivery mechanism and the folded product from another folding mechanism to a different delivery mechanism.

50 44. A sheet folding and delivery mechanism including in combination a plurality of cooperating folding cylinders, means thereon for taking the web leads from a printing press, a plurality of delivery mechanisms, and means for delivering the folded product from one folding mechanism to one delivery mechanism and the folded product from another folding mechanism to a different delivery mechanism, or for delivering the folded products from a plurality of folding devices to a single delivery mechanism.

60 45. A sheet folding and delivery mechanism including in combination a plurality of cooperating folding cylinders, means on each of said cylinders coacting with means on another cylinder to cut sheets from a web, a plurality of delivery mechanisms, and means for delivering the entire folded product to one delivery mechanism or a part

thereof to each of a plurality of folding mechanisms.

70 46. A sheet folding and delivery mechanism including in combination a plurality of cooperating folding cylinders, means on each of said cylinders coacting with means on another cylinder to cut sheets from a web, a plurality of delivery mechanisms, and means for delivering a folded product to one delivery mechanism and a succeeding folded product to another folding mechanism.

80 47. A sheet folding and delivery mechanism including in combination a plurality of cooperating folding cylinders, means on each of said cylinders coacting with means on another cylinder to cut sheets from a web, a plurality of delivery mechanisms, and means for delivering successive folded products alternately to different folding mechanisms.

90 48. A sheet folding and delivery mechanism including in combination a plurality of cooperating folding cylinders, means on each of said cylinders coacting with means on another cylinder to cut sheets from a web, a plurality of delivery mechanisms, and means for delivering the folded product from one folding mechanism to one delivery mechanism and the folded product from another folding mechanism to a different delivery mechanism.

100 49. A sheet folding and delivery mechanism including in combination a plurality of cooperating folding cylinders, means on each of said cylinders coacting with means on another cylinder to cut sheets from a web, a plurality of delivery mechanisms, and means for delivering the folded product from one folding mechanism to one delivery mechanism and the folded product from another folding mechanism to a different delivery mechanism, or for delivering the folded products from a plurality of folding devices to a single delivery mechanism.

110 50. A sheet folding and delivery mechanism including in combination two cylinders, sheet cutting means having one member thereof mounted on one of the cylinders and the other member thereof mounted on the other cylinder, sheet taking and releasing means on each cylinder, folding blades on each of said cylinders, a pair of folding-off rollers cooperating with one of said cylinders and a pair of folding-off rollers cooperating with the other of said cylinders.

120 51. A sheet folding and delivery mechanism including in combination two cylinders, sheet cutting means having one member thereof mounted on one of the cylinders and the other member thereof mounted on the other cylinder, sheet taking and releasing means on each cylinder, and cooperating delivery means for optionally taking a single folded product from both cylinders.

130 52. A sheet folding and delivery mecha-

- nism including in combination two cylinders, means for taking the successive web leads from a printing press, sheet cutting means having one member thereof mounted on one of the cylinders and the other member thereof mounted on the other cylinder, sheet taking and releasing means on each cylinder, folding blades on each of said cylinders, a pair of folding-off rollers cooperating with one of said cylinders and a pair of folding-off rollers cooperating with the other of said cylinders. 58. A sheet folding and delivery mechanism including in combination a cylinder having a plurality of circumferentially disposed sheet supporting means, a cooperating cylinder having a different number of circumferentially disposed sheet supporting means, means for taking the successive running web leads from a printing press optionally on a single cylinder or on both cylinders, folding devices on both cylinders, and cooperating delivery means for taking a folded product from one cylinder or from both cylinders. 70 75
53. A sheet folding and delivering mechanism including in combination two cylinders, means for taking the successive longitudinally folded web leads from a printing press, sheet cutting means having one member thereof mounted on one of the cylinders and the other member thereof mounted on the other cylinder, sheet taking and releasing means on each cylinder, folding blades on each of said cylinders, a pair of folding-off rollers cooperating with one of said cylinders and a pair of folding-off rollers cooperating with the other of said cylinders. 59. A sheet folding and delivery mechanism including in combination a cylinder having a plurality of circumferentially disposed sheet supporting means and corresponding sheet taking and releasing means and folding means, and a cooperating cylinder having a different number of circumferentially disposed sheet supporting means and sheet taking and releasing means, and folding means. 80 85
- 25 54. A sheet folding and delivering mechanism including in combination a cylinder having a plurality of circumferentially disposed sheet supporting means and corresponding sheet taking and releasing means and folding means, and a cooperating cylinder having a different number of circumferentially disposed sheet supporting means and sheet taking and releasing means, and folding means. 60. A sheet folding and delivery mechanism including in combination a cylinder having a plurality of circumferentially disposed sheet supporting means, a cooperating cylinder having a different number of circumferentially disposed sheet supporting means, means for taking the successive running web leads from a printing press directly on a cylinder, sheet cutting means, optionally usable sheet collecting means, and folding devices for folding off a product from either cylinder, or the product from a single cylinder. 90 95 100
- 35 55. A sheet folding and delivery mechanism including in combination a cylinder having a plurality of circumferentially disposed sheet supporting means and corresponding sheet taking and releasing means and folding means, and a cooperating cylinder having a different number of circumferentially disposed sheet supporting means and sheet taking and releasing means, and folding means. 61. A sheet folding and delivery mechanism including in combination a cylinder having a plurality of circumferentially disposed sheet supporting means, a cooperating cylinder having a different number of circumferentially disposed sheet supporting means, means for taking the successive running web leads from a printing press optionally on a single cylinder or on both cylinders, sheet cutting means, optionally usable sheet collecting means, and folding devices for folding off a product from either cylinder, or the product from a single cylinder. 105 110 115
- 40 45 56. A sheet folding and delivery mechanism including in combination a cylinder having a plurality of circumferentially disposed sheet supporting means, a cooperating cylinder having a different number of circumferentially disposed sheet supporting means, means for taking the successive running web leads from a printing press directly on a cylinder, sheet cutting means, and folding devices for delivering a single product or two products. 57. A sheet folding and delivery mechanism including in combination a cylinder having a plurality of circumferentially disposed sheet supporting means, a cooperating cylinder having a different number of circumferentially disposed sheet supporting means, means for taking the successive running web leads from a printing press directly on a cylinder, sheet cutting means, and folding devices for 120
